UNITED STATES PATENT OFFICE.

MARIUS RATIGNIER AND MARIUS CLERC-RENAUD, OF LYONS, FRANCE.

MACHINE FOR FINISHING FABRICS.

SPECIFICATION forming part of Letters Patent No. 727,443, dated May 5, 1903.

Application filed April 30, 1901. Serial No. 58,157. (No model.)

To all whom it may concern:

Be it known that we, MARIUS RATIGNIER and MARIUS CLERC - RENAUD, citizens of France, residing at Nos. 61 and 63 Rue Louis Blane, Lyons, France, have invented a new and useful Machine for Finishing Fabrics, of which the following is a full, clear, and exact description, and for which we have made application for patent in France, dated February 18, 1901; in Germany, dated March 14, 1901; in Italy, dated March 12, 1901, and in Switzerland, dated March 11, 1901.

Our invention is applicable to the operation in use in the dressing or finishing of fabrics, which consists in producing successive bends or slopes in opposite directions of the threads composing these fabrics, either to establish the parallelism of these threads or to separate them from each other when they have been sized in the dressing operation. The machine which we have made to this purpose is based upon the known principle of the undulating course of the fabric in a horizontal plane. However, while the known machines have the purpose to expand by degrees the fabric during its course the essential characteristic point of our machine is maintaining the weft-threads parallel to each other and of constant length while the warp-threads are caused to assume successive inclinations in contrary directions. The result is that the tension in width of the fabric, regulated at the beginning of the operation, is maintained constant, and the work is done more regularly and without danger of tearing, even of very light fabrics.

We will describe our invention by the aid of the accompanying drawings, in which—

Figure 1 is a plan of the machine. Fig. 2 is a vertical section of the nippers conducting the fabric. Fig. 3 is a front view of said nippers, and Fig. 4 is an arrangement for opening the nippers.

The machine consists mainly of two endless chains *a b*, Fig. 1, each passing around drums *c d* on vertical axles mounted at the ends of two parallel frames *g h*. These chains receive motion at equal speed and in the direction indicated by the arrows by means of gearing acting simultaneously on the two drums *c c*. The chains *a b*, the construction of which will be hereinafter described, carry

along their entire length small nippers *ii*, very close together, to grip the edges of the fabric. By an arrangement which will be explained 55 these nippers open when passing the drums *c* and *d* and are closed by springs during the remainder of their course. The portions of the chains which pass along the interior of the frames are parallel and receive on a 60 portion of their length an undulating direction by passing around a certain number of pulleys *m n*, placed symmetrically along each frame. Thus it will be understood that if the two edges of a fabric are gripped by the 65 nippers at *ee* on leaving the drums *d* this fabric will be conducted by the chains, the nippers of which successively grip it at the same points *ee* and will follow the undulations formed by these chains and then their straight 70 part without ceasing to be held. At the end of the machine the nippers by opening at *ff* release the fabric, which will be wound up by known means after, if required, having passed through a drying apparatus. The two chains 75 *a* and *b* being parallel and receiving equal speed it will be readily understood that the weft-threads will remain parallel with each other during the entire operation and will constantly preserve the same length and tension. The warp-threads will follow a direction *jk* parallel with the chains *a* and *b* and will receive successively in the undulated part different inclinations on the weft-threads, so as to produce the desired effect. In the 85 straight part following the pulleys *m n* the warp-threads become again right angles with regard to the weft-threads, and the obtained effect can be fixed by heat or otherwise.

To regulate the width apart of the chains 90 *a b* to the width of the fabric, the two frames *g* and *h* move parallel with each other on carriages *rr*. The dimensions of these undulations is regulated by causing each pair of pulleys *n n* to approach or recede from each 95 other, which pulleys for this purpose are mounted on movable carriages *s s*, operated by screws *s' s'*, and being able to slide horizontally in the frames *g* and *h*. The pulleys *n* can thus move away from or move nearer 100 toward the pulleys *m*, which remain fixed, giving more or less fullness to the undulations. The drums *d d* at the point of entry of the fabric and the guide-pulleys *p p*, fol-

lowing them, are capable of regulation in width apart. To this purpose they are carried by two frames $d'd'$, which can be moved to a small extent transversely on the frames 5 g,h , so as to be able by causing them to approach each other more or less to obtain in passing from the guides p to the pulleys m a widening of the fabric and giving it the desired tension, which will be retained to the 10 outlet of the machine.

The roller l , from which the fabric is unwound, is mounted on a central pivot o , enabling the operative to cause it to oscillate in one or other direction to straighten the 15 badly-placed weft-threads and present them regularly at the entrance of the machine.

We will now describe the construction and arrangement of the nippers i,i , which constitute a new and important part of the machine. These nippers, Figs. 2 and 3, are carried above the endless chain a by prolongations of the vertical axles xx , serving as hinges for this chain. The lower jaw u is carried by a piece v , jointed to the axles x . The upper jaw i is carried by a crank-lever z , jointed to the piece v . A spring y keeps the nipper normally closed with a pressure sufficient to hold the edge of the fabric l .

It will be seen that the nipper is arranged 30 so that the gripping of the fabric takes place in the vertical plane 1 2, Fig. 2, passing through the axles of articulation xx of the chain and nippers. This condition is indispensable in order that the edge of the fabric 35 may follow exactly the axis of the chain in its undulations and that the width of the fabric may be maintained constant.

The combination of the chain a and nippers forms in reality two superposed chains 40 articulated on common axles. The lower chain a passes alone over the different pulleys or drums which guide it. To insure regularity of motion the driving-drums c , Fig. 4, carry teeth 7, gearing with the spaces 6 6,

formed in the chain. The chain formed by 45 the nippers is in free space, which facilitates inspection and separates the fabric from the parts requiring lubrication.

Fig. 4 shows the arrangement employed on the drums c and d to effect the opening of the 50 nippers. On the prolongation of the shaft 3, carrying the drum c , for example, is mounted a circular disk 4 at the height of the arm 5 of the lever z , and of such diameter that it pushes this arm and raises the upper jaw of 55 the nipper. The disk 4, rotating with the drum, exerts no friction on the arm 5, and the motion takes place with all possible smoothness and regularity.

The jointed chains $a b$ may be replaced by 60 bands of leather, metal, or other suitable material or by any other flexible transmission means. In this case the nippers would be fixed on these means and arranged as above described, so as to grip the fabric in the vertical plane of flexion of said means. 65

We would here remark that the invention is not limited to the exact details herein shown and described.

What we claim as our invention, and desire 70 to secure by Letters Patent, is—

In a machine for producing a waving course of a fabric, a pair of endless conducting-chains running parallel with each other in a horizontal plane, means for imparting to said 75 chains a sinuous or waving movement, each of said chains comprising a plurality of links with hinge-rods connecting the same, said rods extending upwardly, and clips carried by the upper ends of said rods, substantially 80 as described.

In witness whereof we have hereunto set our hands in presence of two witnesses.

MARIUS RATIGNIER.
MARIUS CLERC-RENAUD.
